his attorney.

UNITED STATES PATENT OFFICE.

JOHN L. WEINMANN, OF ST. LOUIS, MISSOURI.

SEAL.

1,393,863.

Specification of Letters Patent. Patented Oct. 18, 1921.

Application filed June 6, 1919. Serial No. 302,100.

To all whom it may concern:

Be it known that I, JOHN L. WEINMANN, a citizen of the city of St. Louis, State of Missouri, have invented certain new and useful Improvements in Seals, of which the following is a full, clear, and exact description, reference being had to the accompanying drawings, forming a part of this specification.

10 Figure I is a top plan of my seal strip, as it appears when stamped out for use and before the body of the seal is folded.

Fig. II is an edge view of the seal strip.

15 Fig. III is a perspective view of the seal in closed condition.

Fig. IV is an enlarged longitudinal section through the seal in closed condition.

In the drawings A designates my seal strip as it appears before being folded in 20 a manner to be hereinafter explained to provide for the formation of holding members, by which the tongue of the shackle is held. The said strip comprises a body *a* and a shackle forming tongue *a'*. The body of the 25 strip adjacent the tongue *a'* is struck up to form a raised keeper 1, and extending through said body at the rear end of the keeper is a transverse opening 2.

In forming the seal from the strip A, I 30 bend the body portion of the strip on a transverse line *b* contiguous to the opening 2, and fold what I will term the catch section 4 rearwardly against the keeper section 3. I then fold the body *a* on a line *c* to 35 form a rear guard section 5, which lies against the back of and protects the intermediate catch section 4. The several sections 3, 4 and 5 are secured to each other in any suitable manner after the folds have 40 been made to produce them, and as a most economical means of fastening the sections together, I punch holes 6 through the several sections and upset the spurs produced by the punching operation to form rivet 45 members 7 (see Fig. IV), located back of the guard section 5, of the seal. The holes just referred to are preferably formed so that they extend through the keeper section 3 at opposite sides of the keeper 1, as seen 50 in Fig. III, and therefrom through the sections 4 and 5.

In forming the seal strip I strike therefrom a tang 8, which is so disposed that it lies in the catch section 4 and projects forwardly upon said section when the body of the strip is folded, as explained, and lies

within the keeper 1 of the keeper section 3, as seen in Fig. IV. Also in forming the seal strip I produce in the tongue of the strip apertures 9 through which the tang 8 is adapted to extend when the tongue of the strip is bowed into shackle form and inserted through the keeper 1 of the keeper section 3. These apertures 9 extend transversely of the tongue *a'*, and immediately 60 adjacent to them are raised portions 10 struck from the tongue to furnish passage ways through which the tang 8 on the catch section 4 may move in entering the apertures 9 in the tongue. 70

When the body of the seal has been folded to produce the sections 3, 4 and 5, the tongue of the seal extends rearwardly from the keeper section 3, and in putting the seal in service it is only necessary to loop the tongue 75 *a'* so that its end may be inserted through the rear end of the keeper 1, and after passing beneath the keeper emerge therefrom through the opening 2. In so doing I provide a shackle formed from the tongue *a'*, 80 said tongue extending through the keeper 1, and between the front of the keeper and the portion of the catch section 4 immediately back of the front of the keeper and which is occupied by the tang 8. In inserting the 85 tongue of the seal through the keeper 1, the tongue traverses the tang 8, and upon any attempt to withdraw the tongue from said keeper, the tang 8 enters one of the apertures 9 and prevents the withdrawal of said 90 tongue. The latter is therefore so held as to be securely held against backward movement, with the result of effectually preventing the opening of the seal.

I preferably provide a number of the 95 apertures 9 in the tongue *a'* in order that a larger or smaller shackle may be provided, as may be desired or required.

I claim:

A seal comprising a strip having a comparatively wide part at one end thereof, said wide part having end portions and an intermediate portion, said intermediate portion being folded upon one of the end portions and the other end portion being folded upon the intermediate portion whereby the intermediate portion is interposed between the said end portions, and one of said end portions being provided with a raised portion in the form of a channel, extending 105 from one end of said end portion to the other end thereof, the last mentioned end 110

portion being provided with an aperture at the inner end of said channel whereby a keeper is formed, rivets securing said end and intermediate portions together, a tongue extending from the intermediate portion, and a sealing strip extending from said channel and provided with open ended de-

pressions to act as catches to be engaged by said tongue when the said sealing strip is inserted into said keeper.

10

In testimony that I claim the foregoing I hereunto affix my signature.

J. L. WEINMANN.
